TREATMENT OF HYDROCARBONS

Donald L. Pennington and Wayne L. Benedict,
Chicago, Ill., assignors to Universal Oil Products Company, Chicago, Ill., a corporation of Delaware

No Drawing. Application December 31, 1937,
Serial No. 182,920

12 Claims. (Cl. 196—30)

This invention relates particularly to the treatment of the lower boiling naphthas and gasolines produced in the straight run distillation and in the cracking of petroleum though it may also be applied to analogous low boiling distillates produced in the primary distillation of any naturally occurring hydrocarbonaceous materials or in the secondary distillation of their primary tars.

10 More specifically the invention is concerned with improved methods for treating crude primary gasoline boiling range distillates to render them sufficiently stable and pleasing in appearance and odor from a sales standpoint.

13 Primary naphthas and gasolines quite uniformly require some type of chemical treatment to eliminate objectionable constituents of a colored, odorous or gummy character. The question of the cause of color is still in dispute although it

20 has been variously attributed to suspended asphaltic and resinous materials, oxidized hydrocarbons, nitrogen compounds and even to some pure hydrocarbons. The objectionable odors are principally due to sulfur compounds of which the

25 chief offenders are the sulfur alcohols or mercaptans. The gummy or potential gum-forming constituents are probably heavy hydrocarbon polymers or highly unsaturated hydrocarbons such as conjugated diolefins respectively.

30 It is the object of all chemical treatments to remove sufficient quantities of the groups of impurities mentioned above until they are reduced to a point corresponding to a finished gasoline. The application of so-called "sweetening" agents

35 may be practiced either before or after the distillation following acid treatment or may be applied to distillates which have not received any acid treatment. These "sweetening" reagents apparently transform the foul smelling mercaptans into the relatively odorless and stable dialkyl disulfides by chemical reactions involving oxidation with the removal of the mercaptan hydrogen and the condensation of the residual radicals.

40 45 One of the oldest and best known sweetening treatments involves the use of sodium plumbite solutions followed by the addition of minimum amounts of sulfur to precipitate lead from the initially formed lead mercaptides and form the desired organic disulfides. Owing to the numerous operating difficulties attending the use of plumbite such as the tendency to emulsion formation and the danger of having to use too much sulfur to "break" the lead from solution, numerous other sweetening treatments have been pro-

posed and some have attained commercial importance. The use of hypochlorites has been found applicable to certain distillates, principally those of a straight run character and a later development has involved the use of copper compounds and it is with improvements in this last named type of sweetening process that the present invention is concerned.

5 In one specific embodiment the present invention comprises the treatment of copper-sweetened hydrocarbon oils for the removal of color and undesirable dissolved constituents therefrom by percolating said hydrocarbon oils through beds of granular solid contact materials comprising as their active constituent the salts of ortho phosphoric acid such as for example ammonium phosphates and the various phosphates of the alkali and alkaline earth metals.

10 Owing to the relatively small percentages of compounds involved in the sweetening reactions, the course of copper-sweetening from the chemical standpoint is not entirely certain. In such sweetening processes a large number of copper compounds may be employed either in a dry state or in solution and while in some cases there may be actual removal of sulfur by combination with copper, there may in other cases be merely the formation of copper mercaptides or a true oxidizing action depending upon the character of the copper salt employed. It is therefore not possible to state exactly what reaction products are present in a copper-sweetened gasoline such as, for example, a cracked gasoline, to cause an increase in color in the treated product, but it has been quite generally observed that this increase in color occurs. There are some indications that it may be due to copper mercaptides and that it may be due in part to oxidized compounds depending upon the copper compounds employed and the conditions of treatment. However, it has been found that color of copper-sweetened gasolines is practically always reduced to a minimum by the proper use of granular phosphates through which the sweetened distillate is percolated.

15 20 25 30 35 40 45 50 55 The invention comprises generally the use of any of the phosphates of the alkali or alkaline earth metals and ammonium though it is not intended to infer that all of the compounds which may be used alternately will have exactly the same effects in the secondary treatment of copper sweetened gasolines. As a rule the acid phosphates give the best results and of those included in the group mentioned, the mono-ammonium-dihydrogen ortho phosphoric acid appears to be

one of the best reagents. Owing to the uncertain character of the contaminating materials present in the distillates sweetened by copper, it is not possible to state exactly what chemical or physical reactions may be involved in the use of the granular phosphates as secondary reagents, and no attempt will be made to offer an exact explanation of the action. There may be some transposition of bases or some direct chemical action of the phosphates on the colored materials, but such possible reactions have not been checked by analytical work and reliance is merely placed on the observed results. Since sour stocks to be treated by the copper method will vary widely in composition, particularly in regard to the mercaptan content both in regard to quantity and to quality, it is obvious that the products of the sweetening reactions will vary correspondingly and that different phosphates in the groups mentioned may have entirely different effectiveness when dealing with different charging stocks.

In applying the process of the invention the phosphates are preferably employed in finely divided condition mixed with spacing agents of a relatively inert character such as crushed silica, crushed firebrick, fuller's earth, etc. Secondary treatments are brought about by merely passing the copper sweetened distillates through the granular secondary reagents which are preferably contained in vertical cylindrical treating towers or columns through which the distillates are passed downwardly at ordinary temperatures. While, as a general rule, the phosphate reagents will treat a sufficiently large amount of copper sweetened distillate to permit discarding it at the end of its period of usefulness, the invention may further comprise the use of any necessary reactivation or recovery steps to regenerate the phosphates for reuse.

40. The following example is given to illustrate results obtainable in the use of the compounds characteristic of the invention in effecting further purification of copper sweetened distillates. While the data are entirely representative, it is not intended that they shall impose undue limitations upon the invention's proper scope.

A cracked gasoline produced from stocks from the Mid-Continent-West Texas area was first sweetened by passage through a composite material containing crystalline copper sulfate, ammonium chloride, crushed firebrick, and some water. It was then passed through a mixture of equal parts by weight of finely divided granular mono-ammonium-dihydrogen ortho-phosphate and 55 pumice and the following tabulation of data includes some of the significant properties of the gasoline (1) before any treatment, (2) after the copper sweetening, and (3) after the final treatment in accordance with the invention.

60		Secondary treatment	Mid-Continent-West Texas cracked gasoline		
			Color saybolt	Induction period in oxygen bomb, min.	
				No inhibitor	+0.015% commercial inhibitor
65					
70	1 Sour	None	-2	85	100
	2 Copper sweetened.	do	Red	140	280
	3 do	Ammonium phosphate.	-5	165	340

From the above data it can be seen that the use of the ammonium phosphates as a secondary treating reagent improved the color considerably over the color of the gasoline after the copper sweetening, also that it improved the induction period somewhat when no inhibitor was employed, and still more when a small amount of inhibitor was employed as is customary in most oil refineries. It is to be noted that the inhibitor susceptibility is considerably better in the case of the sample subjected to the final treatment with ammonium phosphate, there being an increase in induction period of 140 minutes when the inhibitor was added to the sweetened material before the final treatment and an increase of 185 minutes when the same amount of inhibitor was added after the final treatment.

The nature of the present invention and its practical possibilities are evident from the foregoing description and numerical data, neither of which is intended to unduly limit its proper scope.

We claim as our invention:

1. A method for the refining of hydrocarbon distillates which comprises subjecting the distillate to the sweetening action of a copper compound and thereafter treating the distillate with a salt of ortho phosphoric acid to remove objectionable reaction products of the copper sweetening.

2. A method for the refining of hydrocarbon distillates which comprises subjecting the distillate to the sweetening action of a copper compound and thereafter treating the distillate with an ammonium salt of ortho phosphoric acid to remove objectionable reaction products of the copper sweetening.

3. A method for the refining of hydrocarbon distillates which comprises subjecting the distillate to the sweetening action of a copper compound and thereafter treating the distillate with an alkali metal salt of ortho phosphoric acid to remove objectionable reaction products of the copper sweetening.

4. A method for the refining of hydrocarbon distillates which comprises subjecting the distillate to the sweetening action of a copper compound and thereafter treating the distillate with an alkaline earth metal salt of ortho phosphoric acid to remove objectionable reaction products of the copper sweetening.

5. A method for the refining of hydrocarbon distillates which comprises subjecting the distillate to the sweetening action of a copper compound and thereafter treating the distillate with an acid salt of ortho phosphoric acid to remove objectionable reaction products of the copper sweetening.

6. A method for the refining of hydrocarbon distillates which comprises subjecting the distillate to the sweetening action of a copper compound and thereafter treating the distillate with mono-ammonium-dihydrogen ortho-phosphate to remove objectionable reaction products of the copper sweetening.

7. A method for the refining of hydrocarbon distillates which comprises subjecting the distillate to the sweetening action of a copper compound and thereafter contacting the distillate with a solid granular material containing a salt of ortho-phosphoric acid to remove from the distillate objectionable reaction products of the copper sweetening.

8. A method for the refining of hydrocarbon distillates which comprises subjecting the distillate to the sweetening action of a copper com-

ound and thereafter contacting the distillate with a solid granular material containing an ammonium salt of ortho phosphoric acid to remove from the distillate objectionable reaction products of the copper sweetening.

9. A method for the refining of hydrocarbon distillates which comprises subjecting the distillate to the sweetening action of a copper compound and thereafter contacting the distillate with a solid granular material containing an alkali metal salt of ortho phosphoric acid to remove from the distillate objectionable reaction products of the copper sweetening.

10. A method for the refining of hydrocarbon distillates which comprises subjecting the distillate to the sweetening action of a copper compound and thereafter contacting the distillate with a solid granular material containing an alkali earth metal salt of ortho phosphoric acid to

remove from the distillate objectionable reaction products of the copper sweetening.

11. A method for the refining of hydrocarbon distillates which comprises subjecting the distillate to the sweetening action of a copper compound and thereafter contacting the distillate with a solid granular material containing an acid salt of ortho phosphoric acid to remove from the distillate objectionable reaction products of the copper sweetening.

12. A method for the refining of hydrocarbon distillates which comprises subjecting the distillate to the sweetening action of a copper compound and thereafter contacting the distillate with a solid granular material containing mono-ammonium-dihydrogen ortho-phosphate to remove from the distillate objectionable reaction products of the copper sweetening.
